United States Patent Office.

JAMES RANEY, OF NEWCASTLE, PENNSYLVANIA, ASSIGNOR TO HIMSELF,
LEANDER RANEY, AND BOSTIC RANEY.

Letters Patent No. 77,654, dated May 5, 1868.

IMPROVEMENT IN ELEVATING FLOUR, FEED, GRAIN, &c.

The Schedule referred to in these Letters Patent and making part of the same.

TO ALL WHOM IT MAY CONCERN:

Be it known that I, JAMES RANEY, (assignor to myself, Leander Raney, and Bostic Raney,) of Newcastle, in the county of Lawrence, and in the State of Pennsylvania, have invented certain new and useful Improvements in Ventilating Millstones; and do hereby declare that the following is a full, clear, and exact description thereof, reference being had to the accompanying drawings, and to the letters of reference marked thereon.

In the annexed drawings, making part of this specification, A represents a substantial frame, which is intended to support the stones of an ordinary flouring or other mill. C represents one of the stones of a mill, and B the hoop, which surrounds it, both of which may be made and arranged in any of the well-known and usual ways.

Beneath the stone, and connected with the frame A, is a fan-box, E, in which is placed a fan, F. The arms of this fan, it will be seen, after leaving the fan-shaft a little distance, turn at right angles.

Leading down from the stones is a discharge-spout, D, (seen in dotted lines, fig. 1,) through which the ground material passes from the stones. This spout leads into the fan-box, around or about the eye of the shaft. G represents a spout, which connects at its lower end with the fan-box. The upper end of this spout is curved, and leads through a chamber, H, the upper portion of the spout, at one point, where it passes through said chamber, being removed, so that air can escape when a surplus is used or forced through the spout. The ground material passes out of the spout through the orifice at G'. The fan is revolved rapidly by power, and receives air into it through an orifice at a, near or at the upper end of spout D, and just outside of the hoop B. The spout G may lead up as high as it may be desirable to carry the material.

The material is thoroughly ventilated by the time it passes through the fan and out of the spout G, and issues well cooled.

H represents a chamber, which may be made of any suitable size, and covered with canvas, or other suitable material. From this chamber a spout, I, leads down between the stone and the hoop. This spout is provided with a slide-valve, J, to open or close it at pleasure.

A spout, K, which is also provided with a suitable valve, leads from chamber H down into the fan-box. The object of spout I is to convey any surplus air or draught which enters chamber H, through spout G, into the hoop, or between the hoop and the stone for cooling purposes and ventilation. Should this not be desirable, at any time, the valve J can be closed, and the surplus draught will pass down through spout K into the fan-box again. By opening and closing the valves of the two spouts I and K, to suit the case, air can be carried either between the stone and the hoop, or directly into the fan, or partially in both directions.

Having thus fully described my invention, what I claim as new, and desire to secure by Letters Patent, is—

The arrangement of the fan E, spout G, and chamber H, with the spouts I, K, and D, as and for the purposes herein set forth.

In testimony that I claim the foregoing, I have hereunto set my hand, this 18th day of March, 1868.

JAS. RANEY.
